UNITED STATES PATENT OFFICE.

WILLIAM H. SMYTH, OF BERKELEY, CALIFORNIA, ASSIGNOR TO HUMPHREY GAS PUMP COMPANY, A CORPORATION OF NEW YORK.

UTILIZING HEAT ENERGY.

1,037,070.

Specification of Letters Patent. Patented Aug. 27, 1912.

Application filed February 5, 1900. Serial No. 4,127.

To all whom it may concern:

Be it known that I, WILLIAM H. SMYTH, mechanical engineer, citizen of the United States, residing at Berkeley, in the county 5 of Alameda and State of California, have invented certain new and useful Improvements in Utilizing Heat Energy; and I do hereby declare the following to be a full, clear, and exact description of the same.

10 This invention relates to the art of process of utilizing the expansive force of heat. It also involves improvements in dynamics as embodied in heat motors; pneumatics as in air compressors and other gas apparatus; hydraulics as in pumps and other water devices.

15 In the devices and methods adopted heretofore, in utilizing heat as a source of power, an exceedingly large proportion of the heat value of fuels has been wastefully 20 dissipated.

25 The present invention is a radical departure from the accepted practice having for its object the utilization of much of this heretofore wasted heat energy.

30 In general terms the objects of the invention are to effect high initial and especially low terminal temperatures of an inflamed charge, and to transform this wide range into an equivalent of useful work. It aims to utilize a larger percentage of the fuel heat value, by providing conditions in harmony with the requirements for harnessing heat energy as displayed in explosive action.

35 Incidental to the main object of the invention and more fully stated, some of the objects are to provide conditions in the utilization of explosive energy to effect:—high initial temperature and pressure; low terminal temperature and pressure; expansion below atmosphere; high piston speed; immediate conversion of the fugitive energy of explosion into a stable form of practically 40 available pressure; compression of charge prior to ignition; prior compression of charge in proportion to the resistance to be met by its expansion during inflaming; compression automatically produced, regulated and controlled by the resistance to be over- 45 come; expansion commensurate with varying initial temperatures and pressures; extreme mobility and responsiveness of piston to initial pressure; transmitting association between piston and power storing or utilizing means providing for the resistance being

applied with increasing intensity; complete scavenging of spent or used gases.

These objects are attained and other important results are effected whereby the art or process is made available in the arrangement of the simple means shown in the accompanying drawings in which:—

Figure 1 is a side view of a single cylinder apparatus, largely in section to more clearly illustrate it. Fig. 2 is an elevation of a two cylinder or duplex apparatus having a common air chamber and charging mechanism. Fig. 3 is a series of diagrams illustrating the cycle of operations or steps in the process as carried into effect in the apparatus shown in Fig. 2. Fig. 4 is a series of diagrams illustrating variants of the single and multiple apparatus adapted to carry into effect the herein disclosed art or process.

Referring to the drawing, 1 is a cylinder (using this term conventionally) of any suitable form, which constitutes a charge, explosion or expansion chamber. This cylinder is prolonged into an easy curve 2, and the curve 2 is tapered to a nozzle outlet 3 directed upward. The nozzle 3 projects into and is surrounded by a casing or uptake 4 tapering in the opposite direction, from the neighborhood of the nozzle, to form an injector on a large scale. At the lower end of 45 casing 4 is placed a suitable check valve 5 and strainer 6, and at the upper end of the casing another check valve 7. An air inlet valve 5^a is provided, opening into the explosion and expansion chamber or its extension. The structure thus described from its commencement, around the curve to the valve 7 comprises the charge and expansion chamber. Above the check valve 7 is placed an air-chamber 8. A pipe 9 connects the air 50 chamber 8 with the casing 4 below the valve 7. A valve 10 is provided on the pipe 9 to control the flow of air or water from the chamber 8 into the casing 4. A suitable independent freely movable piston is located 100 in chamber 1. In the present form of the device illustrated in Figs. 1 and 2, when in position and operation this piston consists of a volume of fluid, preferably water. Means are also provided for changing or 105 regulating the position of the surface of this piston in chamber 1. In the present instance as illustrated in Figs. 1 and 2 it is shown as piston 11, movable in a cylinder in communication with the chamber 1, so that 110

the fluid piston, though entirely independent and free to move in response to heat pressure impulse, is also under control as to its position. Power connections are represented by a rock-shaft 12, with levers to operate piston 11 and the various valves for controlling the charges and effecting the ignition.

As illustrated in Fig. 2 the piston 11 is provided with a rod 13 which extends through a stuffing-box 14 in the side of the device. The rod 13 in this form is connected to a motor cylinder 15 by suitable connections such as links 16, levers 17, rock-shaft 12, link 18 and the piston rod 19 as illustrated in the forms either Fig. 1 or Fig. 2.

A pipe 20 forms an outlet for the chamber or chambers 8. The chambers 8, if more than one, are connected so as to form one air chamber of large size compared with the volume of the water-piston. In other words the piston should always be of relatively small size as compared with the resilient cushion of the air chamber. To operate in proper sequence the other working or controlling devices, I provide the following described mechanism. A cam lever and tappet 21 is attached securely on shaft 12 having cam surfaces 21^a and 21^b. A plug valve 22 is common to and controls the flow of gases to or from the two explosion chambers. It is shown connected to the explosion chamber in Fig. 1 by pipe 23. A check valve 24 controlling the admission of the explosive charge, is provided with a spring actuated valve stem 25, as shown in Fig. 1.

The operating lever or handle 22^a is secured to the plug or stem of the valve 22. A slotted link 22^b is loosely connected to 22^a and engages with one arm of a loosely pivoted bell-crank tappet lever 22^c. The other arm of the lever 22^c constitutes a tappet which engages with the part 21^a of the cam ended lever 21 to be operated thereby at each arc reciprocation of the cam end of the lever. This cam end serves the double function of reversing the four-way valve 22 and raising and keeping the valve 24 open, by engagement of the cam surfaces 21^a and 21^b with the stem connections of valves 22 and 24 respectively. This is shown in Fig. 1. A vaporizer or fuel mixer 26 is connected to a fuel reservoir 27 by a suitable valve controlled pipe. Figs. 1 and 2.

A tappet arm 28 is secured to shaft 12 and is adapted to engage and operate tappet lever 35. 29 is an ignition chamber connected to the explosion chamber 1 by pipe 23 but separable therefrom by valve 22. A sparking device shown as consisting of a metallic rocking wiper 30 is provided in the ignition chamber and in the path of the ingoing explosive gas, but removed from the path or splash of the water. This rocking wiper 30 is secured on shaft 31, which extends through the side of the ignition

chamber and is provided with an operating lever 32, on its outer end. The other element of the sparking device consists, as shown, of a flat spring 33 attached to an insulated rod 34 passing to the outside of the ignition chamber. 35 is a tappet lever secured upon the spindle of each of the valves 10. 36 is a link slotted at each end for the reception of the pin 37 on the tappet levers 35. The link 36 is provided with a pin 38 approximately midway of its length, which engages with the lever 32 of the spark wiper, Figs. 1 and 2. A battery or other suitable source of electrical energy is represented by 39, and 40 and 41 are wires leading to the wiper and spring respectively. A yoke 42 is secured upon the piston-rod 13 and its ends are pivotally connected to the rods 16, Fig. 2.

A plug valve 43 is placed in a pipe 44 which connects the opposite ends of cylinder 15, and a pipe 45 connects the valve and the cylinder ends with a source of pressure. An exhaust pipe for the four way valve 43 is shown at 46 which permits each end of cylinder 15 to exhaust alternately. An operating lever 47 is provided for valve 43, which is connected to a sliding tappet rod 48 having springs 49 and tappets 50. Levers 51, hinged at one end and each provided, at or near that end with a cam surface 52, are provided. The opposite end of each lever is provided with a wedge-shaped latch, to engage with tappets 50. A tappet 53 is secured upon one of the rods 16, to engage with and release the latch levers 51 alternately. All of which is clearly shown in Fig. 2.

In Fig. 1 is shown a complete operative unit or single cylinder device. All the working parts are in operative association. Thus, from this view, being partly in section, the construction of the device and the steps of the process will be clearly understood. The course of the explosive charge and the water can also clearly be followed from their sources to their outflow. In this view the main body of the explosion chamber 1 is shown entirely submerged, its small extension or ignition tube 23 alone appears above water. In this view also, the charging cylinder is shown connected directly with the explosion or combustion chamber 1. The discharge pipe 20 leads from the air chamber 8 near the bottom thereof but sufficiently above the valve 7 to provide a water seal thereto. The air chamber 8 and the various pipes are shown broken to indicate that these pipes may be made longer or shorter to meet the requirements of the conditions under which the device is to be operated, and whether it is to be operated purely as a force pump or as partly "suction" and partly force.

The cycle of operation and the steps of

the process as exemplified in the two-cylinder apparatus is illustrated in the diagrammatic series Fig. 3, in which for simplicity and clearness, the details of mechanical construction have been omitted. These diagrams will assist in making clear the operation of the described apparatus and a ready comprehension of the arrangement, purpose and functions of the various mechanical details hereinbefore set out.

10 I. Shows the device taking an explosive charge in the left hand cylinder and discharging the spent gases from the other cylinder, the piston 11 being midway of its stroke, traveling to the right.

15 II. Shows the left hand cylinder with a fresh charge therein, and the right hand cylinder completely occupied by the water piston, the spent gases of the previous explosion having been driven out by the water.

20 III. Shows the charge in the left hand cylinder compressed to less than half of its original bulk by the admission of air pressure between the water piston and the check valve 7.

25 IV. Shows the expansion of the charge due to explosion and the travel of the water into the air chamber, preceded by the volume of air from beneath the valve 7. This diagram also shows the inrush of water through the lower check valve 5 induced by the injector form of the uptake pipe, gravity and atmospheric pressure.

30 V. Shows the left hand cylinder almost filled with water.

35 VI. Shows a condition similar to that of I, but reversed as to the direction of the flow of gases and the movement of the water piston.

40 VII. Shows a charge in the right hand cylinder. The left hand cylinder in this case being completely scavenged of spent gases of the previous explosion.

45 VIII. Shows the explosive charge in the right hand cylinder ready to be ignited, thus completing the cycle.

In the foregoing brief description of the diagrams of Fig. 3, emphasis has not been laid on the operation and function of valve 5^a in the cycle and process, as the question of its use is a matter, largely within the discretion and judgment of the operator and dependent on the nature of the work to be done in relation to the head to which the water is to be forced. It should in practically all cases be used to insure best economy. Its use enables atmospheric pressure to be employed to displace the water in the air chamber to the level of the discharge opening and thereafter supply air absorbed by the water under pressure in the air chamber, and, in addition thereto, it permits the excess of atmospheric pressure over that required to force water into chamber 1 to be

employed in lightening the column and so reducing the resistance to be overcome by the explosive charge.

With the foregoing description of the mechanical construction of the apparatus and its cycle, its mechanical operation and the steps of the process carried into effect thereby, will be simple and apparent to those skilled in kindred arts. A brief description therefore will suffice, of the practical operation of the apparatus and how the process is carried into effect thereby. This will now be given.

Motion is imparted to the piston 11 by the operation of the small engine 15 and by the described or other suitable mechanism, the various valves and other moving parts are worked in proper sequence. The action of the piston 11 causes the fluid piston to move in the chamber 1 and make room for the charge in its chamber.

The valve 22 being properly disposed, the action of piston 11 and the travel of the water piston causes successive inflow of explosive charges and expulsion or scavenging of the spent gases. Assuming as is shown in

90 Fig. 1, the explosive charge to be in chamber 1, the water piston will extend nearly to valve 7, separated from the water and pressure in the air chamber 8 by the valve 7 and by whatever air has been permitted access through valve 5^a.

95 At this point valve 10 (or valves 10 and 10^a of diagram 1 Fig. 3) is opened by engagement of tappet arm 28 with the tappet lever 35, and the compressed air, or water under pressure (or air and water) from the air chamber consequently

100 flows beneath the valve 7. Thus the water piston is forced back against the charge, compressing it to the pressure of the air chamber, which is, of course, that of the head.

105 The charge is prevented from escaping by the closing of valve 24. Thus the water piston while free to respond to the explosive impulse, is under control and movable at will.

110 The charge in the combustion chamber 1 and the air chamber 8 are now under like pressure, which is as has been shown, that due and corresponding to the head to which the liquid is being forced. It

115 may be noticed also that the ignition chamber 29 with its sparker is in free communication with the explosion chamber. Ignition now takes place by the engagement of the tappet pin 37 with the end of the slot in the link 36 thus rocking the wiper 30 past the spring 33 by the connection of the link 36 to wiper arm 32.

120 The slot in 36 permits the valve 10 to close immediately the wiper arm 32 passes out of engagement with the spring 33. By

125 the explosive expansion of the gases, in cylinder 1, the water piston is driven with great energy and speed through the nozzle 3. The entire water piston may be driven out of the expansion chamber through valve

130 7. The size of the expansion chamber is a

matter within the discretion of the builder, having in mind the circumstances under which the apparatus is to work. It may be so proportioned to the discharge, that the expansion may extend so far as to not only drive out the water piston completely, but to permit a portion of the expanded charge to pass into the air chamber during expansion, together with air admitted through the valve 5*.

10 The spaces vacated in chamber 1 and extension 4 are filled instantly (practically simultaneously with the expansion) by air through valve 5*, if this is desired and the valve properly proportioned, or with any desired proportion of air and water. That portion of the air admixed with the spent gases in the part 4 of the expansion chamber will be cut off and separated from that in the charge chamber 1 by the incoming water through valve 5. The portion of air and gas in the extension 4 is thus trapped beneath valve 7, ready to be driven into the air chamber at the next operation of the water piston. That portion of the spent gases and air in chamber 1 will pass out as exhaust. The lengths of the charge chamber 1 and its extension 4 may be so proportioned to each other that as shown in Fig. 1: the extension may facilitate the scavenging of the spent gases and also the introduction of air beneath valve 7 by the gravity of the water piston.

Owing to the poised or balanced condition and the small mass of the water piston, the mobility and responsiveness is extremely great. It offers practically inappreciable resistance to being started into motion and high velocity. It is practically a liquid projectile. Its inertia due to weight and speed causes it to travel, under practical conditions, a distance comparable to the expansion of the same compressed explosive charge exploding and expanding freely in the atmosphere. Thus the terminal pressure in the expansion chamber after the drive of the piston, always runs in practice below that of atmosphere a good vacuum is produced and the economic results accruing thereto. Vacuum, however, in whole or part, is not essential to its operation. When used as illustrated in the various figures, with the normal level of the water piston in the explosion chamber 1 at or below the outside level of the water, vacuum may be dispensed with entirely, (though this is seldom advisable) the gravity of the water supplies the energy required of the atmospheric pressure of vacuum. But even under these circumstances the benefits and economies of vacuum are available with this apparatus. When the device is operated under conditions where gravity can supply the water to the working level in the charge chamber, 65 vacuum is utilized to carry and force at-

mospheric air into the expansion chamber and so beneath the submergence head. In fact vacuum is, in a sense provided as atmospheric air and pressure is permitted free and unrestricted entrance to the expansion chamber during the time that the expansion pressure runs below atmospheric pressure. Vacuum is applicable in low lifts; this is controllable through valve 5* more or less in accordance with the lift.

75 The means and method employed for compressing the charge, bring about a somewhat paradoxical condition, viz that the initial pressure of explosion is exerted against a minimum resistance. This action is due partly to the lowering of the pressure in the air chamber, immediately prior to explosion, below the static pressure of the liquid column and partly to employing the head to compress the charge before ignition.

80 The necessary conditions to ideal economy in explosive engines are thus presented in the invention herein set forth, and in a peculiarly complete manner. The piston speed is mechanically unrestrained. The range of expansion is also unhampered, and is proportional to the resistance. The explosive expansion acts against a minimum initial pressure and with prior compression of the resilient charge equal to the pressure to be met by the exceedingly enhanced pressure due to inflaming.

85 As earlier stated, the invention is broader in scope than its application to raising or moving water; it is equally applicable to raising or moving or overcoming any other form of mechanical resistance. The apparatus described is equally available for handling or compressing gaseous fluids as for moving liquid fluids.

100 Obviously, as in other arts, the apparatus will vary widely in accordance with the specific result desired. A few such variants are diagrammatically illustrated in Fig. 4. Of these, a brief description will now be given.

105 Diagram IX represents an apparatus substantially similar to that shown in Fig. 2, but in which the expansion chamber is so proportioned that the expansion extends 115 beyond valve 7 and to an extent commensurate to reducing the pressure of the expanding gas much below atmosphere. So that during the time that expansion pressure is below atmosphere valve 5* is opened by atmospheric pressure. It admits air and atmospheric pressure into both the expansion chamber and the air-chamber, behind the water piston. The air beneath the piston and above the valve 7 is trapped within the 120 air chamber by the closing of the valve 7, when the energy of explosion has spent in compressing the air in the air chamber. This trapped increment or surplusage of air finds its way out of the air chamber with the 125

water, through the water discharge pipe. The explosion chamber is supplied with a fresh volume of water or water piston through the foot valve by gravity. The compression of the charge is effected as already described with reference to Fig. 2, through the medium of air or water by the pressure of the air chamber.

Diagram X shows a device similar to Diagram IX with the variation of the omission of the inlet and outlet for water. It thus constitutes a double-acting air compressor. In this variant, as it is not desired to transfer water to a higher level, the inlet for water is of course unnecessary, the valve 5 may be closed, or, as shown in the diagram, omitted. The water piston is used continuously being transferred back from the air chamber through the pipe 9. The compressed air is carried off, for use, through pipe 54, from the upper part of the air chamber.

Diagram XI shows a single acting air compressor formed of one cylinder or member of the device illustrated in the preceding diagrams and having a combined solid and fluid piston. In this form valve 5 may act as an inlet for atmospheric pressure upon the bottom or back of the free piston. The piston is permitted to return by gravity. The valve 5^a admits air and allows the piston to fall, and thus provides successive volumes of air to be driven into the air chamber. The compression of the charge is effected by the pipe 9 transferring air from the air chamber beneath valve 7.

Diagram XII is similar to the previous one, omitting only the liquid part of the piston and consequently the curved form of the explosion and expansion chamber. Its operation is similar to that of XI.

Diagram XIII shows an apparatus similar to Diagram XII, but double ended or double acting. The operation in this case is effected, at each end, by the energy of the traveling piston being absorbed by the air cushion at each end of the apparatus, which compressed cushion forms alternately the next explosive charge at each end.

Diagram XIV shows a motor form of the apparatus in which the water piston compresses air alternately on opposite sides of a piston suitably connected to a crank to produce rotary motion from its reciprocation. The water piston is returned as in Diagram X through the pipe 9. The compression of the charge is also effected as in X by the operation of the valves 10—10.

60 In all these variants the charge forming, controlling and igniting devices may substantially conform to those shown in Fig. 1. Some of the novel and useful effects, functions and results disclosed by this invention

are:—The efficiency of the explosive action increased with the increase of the resistance to be overcome. This highly desirable result flows from the increasing compression of the charge by increase of pressure in the air chamber or water column *i. e.* the resistance. The induction of air, at and by atmospheric pressure, beneath a column of liquid, which exerts a static pressure many times that of atmosphere. The introduction of a resilient fluid into a liquid column and the column subjected to explosive or other pressure beneath the point of introduction.

As indicating the scope of this invention, it may be stated that the charging and motor cylinders are not, of necessity, intimately connected with the air chamber or explosion chamber. They may be located at considerable distance therefrom, as for example, on the surface, with the explosion chamber at the bottom of a shaft or well, as illustrated in Fig. 1 by the breaks shown in the pipes.

The whole device may be located at a point distant from that at which the work is being utilized. The compressed air, water or impulse may be carried by pipes to suitable devices at the bottom of a shaft or other distant location.

The displacement of the spent gases by liquid piston or induction of fresh charges thereby, is not of the essence of the invention these functions may be performed in many other ways. One such is illustrated in Fig. 1.

The injector form of construction may not always be desirable nor is it essential.

The U or curved shape of connection between the cylinder and uptake is only one convenient form. The uptake may concentrically or otherwise surround the cylinder, or be entirely omitted as in Diagrams XII and XIII.

The means shown for controlling the fluid piston is not essential, in practice the gravity of the water piston has been used to charge and exhaust the gases, though the means shown have been found positive and reliable.

The work required of the engine 15 is so insignificant that, in many instances, it will be found advantageous to operate a number of explosion chambers, with an engine and valve mechanism common to all, as shown in the various views in which the engine serves for two explosion chambers. In some instances where a source of small power is available in any of the ordinary forms, it may be used with economy to operate the charging and valve admission in a plant of considerable proportions. A wind mill or even hand-power may be made available to supply explosive fuel, and pump large volumes of water rapidly.

These supplementary motor devices serve only to supply the explosive mixture at atmospheric pressure, which function, of course, requires but little power.

5 The apparatus for effecting my said invention may be stationary or portable; it may be employed for locomotion or propulsion in any of its various adaptabilities and under its dynamic, pneumatic, or hydraulic categories.

10 An illustration of another embodiment of the invention involved in the present disclosure, differing in appearance and construction and details, is presented in a companion application for improvement in utilizing heat energy filed Feb. 5, 1900, Serial No. 4129. Reference is also made to another companion application, on the apparatus used herein to illustrate the art or 15 method disclosed herein, filed on the same day bearing Serial No. 4128 under title, utilizing heat energy.

It is not intended to claim in this application the constructions herein illustrated or 20 described, as the art or process set forth may be performed and carried into effect by many other diverse forms of construction. The forms illustrated in the drawings and 25 diagrammatic views hereto attached merely represent convenient apparatus whereby 30 this invention may be usefully employed.

As the invention herein described is a complete departure in the arts referred to, I claim it broadly, unrestricted to the particular forms shown, the particular proportion 35 or arrangement of parts or details of construction.

What I claim is:—

1. The improvement in the art of utilizing 40 the expansive force of heat which consists in, interposing a fluid transmitting device between a compressed fluid explosive charge and an elastic body and then igniting the charge.

2. The improvement in the art of utilizing 45 the expansive force of heat which consists in interposing a fluid, movable at will, between the expansive force and the object against which the force is to be directed.

3. The improvement in the art of utilizing 50 the expansive force of heat which consists in interposing a fluid piston, between a heat generating charge and an elastic cushion, compressing the charge and then igniting it.

4. The improvement in the art of utilizing 55 the expansive force of heat which consists in placing an independent piston, between a combustible charge and an inclosed elastic cushion, compressing the charge and then igniting it.

5. The improvement in the art of utilizing 60 the expansive force of heat which consists in, so placing an independent piston as to transmit the expansive force of a com-

pressed gaseous explosive to an inclosed elastic cushion and then igniting the explosive.

6. The improvement in the art of utilizing 70 the expansive force of heat which consists in, interposing a fluid piston between a gaseous charge and an elastic cushion, compressing the charge by the pressure of the cushion and then igniting the charge.

7. The improvement in the art of utilizing 75 the expansive force of heat which consists in interposing a fluid piston between a gaseous explosive and an elastic cushion, compressing the explosive by pressure generated by a previous explosion and then igniting the gaseous explosive.

8. The improvements in the art of utilizing 80 the force of heat to force liquid to greater head or pressure which consists in supporting a liquid column upon a gas and expanding the gas by heat.

9. The improvement in the art of utilizing 85 the expansive force of heat which consists in supporting a liquid column upon a gas indirectly through an elastic cushion and expanding the gas by heat.

10. The improvement in the art of utilizing 90 the expansive force of heat, which consists in supporting a liquid column upon a gas in an inclosed chamber and interposing a body of air and mobile piston between 95 them and expanding the gas by heat.

11. The improvement in the art of utilizing 100 the expansive force of heat to force liquid to greater head or pressure, which consists in compressing an explosive charge by a liquid column moved by the explosion thereof and then igniting the charge.

12. The improvement in the art of utilizing 105 the expansive force of heat, which consists in interposing an independent piston, movable at will, between an explosive charge and a liquid column to be moved, and then igniting the charge.

13. The improvement in the art of utilizing 110 the expansive force of heat, which consists in interposing a freely movable substantially non-compressible piston, and an elastic cushion between a compressed combustible charge and a liquid column to be 115 moved, and then igniting the charge.

14. The improvement in the art of utilizing 120 the expansive force of heat, which consists in opposing the expansion of a compressed explosive gas by a resilient cushion before ignition and then igniting the gas.

15. The improvement in the art of utilizing 125 the expansive force of heat, which consists in supporting a liquid to be moved upon an expansible charge, interposing an elastic cushion, and then expanding the charge.

16. The improvement in the art of utilizing 130 the expansive force of heat to store energy, which consists in supporting liquid

and a solid piston by gas, exploding the gas against the liquid.

17. The improvement in the art of utilizing the expansive force of heat to store energy, which consists in inclosing gas within a chamber, causing liquid and a solid piston to be sustained by the gas, igniting the gas.

18. The improvement in the art of utilizing the expansive force of heat, which consists in inclosing an explosive gaseous charge within a chamber, supporting liquid upon an elastic cushion, compressing the explosive charge, firing the charge against the cushion.

19. The improvement in the art of utilizing the expansive force of heat, which consists in inclosing an explosive gaseous charge within a chamber, supporting liquid upon an air cushion, interposing a freely movable body between the liquid and the explosive charge, compressing the charge by the resilient force of the air cushion, firing the charge against the cushion.

20. The improvement in the art of utilizing the expansive force of heat, which consists in inclosing and compressing a gas within a chamber, inclosing air within another chamber, interposing a free body between the gas and the air, expanding the gas by heat and restraining the resilience of the air.

21. The improvement in the art of utilizing the expansive force of heat, which consists in inclosing a gas within a chamber, inclosing air within another chamber, interposing a freely movable body between the gas and air, expanding the gas, restraining the resilience of the air, forming a partial vacuum and admitting a fresh volume of air.

22. The improvement in the art of utilizing the expansive force of heat, which consists in inclosing a gas within a chamber, inclosing air within another chamber, interposing a freely movable body between the gas and air, compressing the gas, expanding the gas, restraining the resilience of the air, forming a partial vacuum and admitting a fresh volume of air.

23. The improvement in the art of utilizing the expansive force of heat, which consists in inclosing a gas within a chamber, inclosing air within another chamber, interposing a freely movable body between the gas and air, compressing the gas by the resilient force of the compressed air, expanding the gas, restraining the resilience of the air, forming a partial vacuum and admitting a fresh volume of air.

24. The improvement in the art of utilizing the expansive force of heat, which consists in inclosing an explosive gas within a chamber, inclosing air within another chamber, interposing a fluid piston between the gas and air, compressing the gas by the re-

silient force of the air, igniting the gas, restraining the resilience of the air, forming a partial vacuum, admitting a fresh volume of air and gas respectively at each end of the piston, igniting the successive compressed charges, and repeating this indefinitely.

25. The method of utilizing the expansive force of heat consisting in expanding a compressed charge against an elastic cushion, interposing a body of liquid and continuing the expansion of compressed charges and maintaining the volume of liquid substantially equal for each charge.

26. The improvement in the art of utilizing the expansive force of heat to store energy, which consists in interposing a liquid and a rigid piston between a gas under compression and an elastic cushion and expanding the gas by heat.

27. The improvement in the art of utilizing the expansive force of heat, which consists in, supporting a weight upon a gas indirectly through an elastic cushion and expanding the gas by heat.

28. The improvement in the art of utilizing the expansive force of heat, which consists in, supporting a weight upon a gas in an inclosed chamber and interposing a body of air and free piston between them and expanding the gas by heat.

29. The method which consists in moving liquid by the expansion of a compressed combustible charge, and interposing a rigid piston between the liquid and an expandible medium.

30. A method which consists in compressing an elastic cushion by the movement of liquid actuated by the expansion of a compressed combustible charge.

31. The improvement in the art of utilizing the expansive force of heat, which consists in, inclosing an explosive gas within a chamber, supporting a weight upon an elastic cushion, compressing the explosive gas, exploding the gas against the cushion.

32. The improvement in the art of utilizing the expansive force of heat, which consists in, inclosing an explosive gas within a chamber, supporting a weight upon an air cushion, interposing a freely movable body between the weight and the explosive gas, compressing the gas by the resilient force of the air cushion, exploding the gas against the cushion.

33. The improvement in the art of utilizing the expansive force of heat, which consists in, inclosing a gas within a chamber, inclosing air within another chamber, interposing a freely movable body between the gas and air, igniting the gas, restraining the resilience of the air, forming a partial vacuum in the gas chamber, and admitting air to the vacuum during its formation.

34. The improvement in the art of utiliz-

- ing the expansive force of heat, which consists in inclosing a gas within a chamber, inclosing air within another chamber, interposing a freely movable body between the gas and air, compressing the gas, expanding the gas, restraining the resilience of the air, forming a partial vacuum in the gas chamber, admitting air to the vacuum during its formation.
10. 35. The improvement in the art of utilizing the expansive force of heat, which consists in, inclosing a gas within a chamber, inclosing air within another chamber, interposing a freely movable body between the gas and air, compressing the gas by the resilient force of the compressed air, expanding the gas, restraining the resilience of the air, forming a partial vacuum in the gas chamber, admitting air to the vacuum during its formation.
15. 36. The improvement in the art of utilizing the expansive force of heat, which consists in, inclosing an explosive gas within a chamber, inclosing air within another chamber, interposing a fluid piston between the gas and air, compressing the gas by the resilient force of the air, igniting the gas, restraining the resilience of the air, forming a partial vacuum by the expansion of the gas, admitting air to the vacuum during the expansion of the gas, admitting air and gas respectively at each end of the piston, igniting the successive compressed charges and repeating these steps indefinitely.
20. 37. The improvement in the art of utilizing the expansive force of heat, which consists in, interposing a fluid transmitting device between a compressed fluid explosive charge and an elastic body, then igniting the charge, forming a partial vacuum by the expansion of the charge and admitting air by atmospheric pressure to the vacuum during its formation.
25. 38. The improvement in the art of utilizing the expansive force of heat, which consists in, supporting liquid by gas, exploding the gas against the liquid whereby the liquid is caused to move and produce a partial vacuum by the explosion of the exploding gas, introducing air by atmospheric pressure into the vacuum and mingling the introduced air with the liquid.
30. 39. The improvement in the art of utilizing the expansive force of heat, which consists in, igniting an explosive charge against a liquid column whereby the column is moved and a partial vacuum is formed by the expansion of the charge, introducing air by atmospheric pressure into the vacuum during its formation and mingling the introduced air with the liquid column.
35. 40. The improvement in the art of utilizing the expansive force of heat, which consists in moving a column of liquid by the expansive force of an exploding charge and introducing air into the column of liquid while in motion.
41. The improvement in the art of utilizing the expansive force of heat, which consists in moving a liquid column by explosive energy and simultaneously introducing air into the liquid column.
42. The improvement in the art of utilizing the expansive force of heat, which consists in introducing air into a liquid column and then igniting an explosive mixture against the column whereby it is caused to move.
43. The improvement in the art of utilizing the expansive force of heat, which consists in supporting a weight upon an explosive gas, igniting the gas whereby the weight is caused to move through the expansion of the gas and create a partial vacuum and introducing air into the vacuum during its formation.
44. The improvement in the art of utilizing the expansive force of heat, which consists in igniting a compressed gaseous charge against a liquid column whereby the column is moved and a partial vacuum is formed by the expansion of the ignited charge, introducing air by atmospheric pressure into the vacuum during its formation and mingling the introduced air with the liquid column.
45. The improvement in the art of utilizing the expansive force of heat, which consists in moving a liquid column by explosive energy of a previously compressed charge and simultaneously introducing air into the liquid column.
46. The improved method of raising water or the like, which consists in introducing a resilient fluid into a column of water and applying a lifting pressure other than gravity to the intermingled column below the point of intermingling.
47. The art of raising water or the like, which consists in aerating a column of water and applying a lifting force other than gravity beneath the aerated column.
48. The art of raising water or the like, which consists in aerating a column of water and applying a lifting force other than gravity beneath the column below the point of aeration.
49. The improved method of raising water or the like, which consists in applying an explosive gaseous charge to a column of water, increasing the pressure of the explosive charge until it substantially equals the static head of the column, due to previous explosions, and then igniting the charge.
50. The improved method of raising water or the like, which consists in applying an explosive gaseous charge to a column of water, increasing the pressure of the explosive charge until it substantially equals the static head of the column, separating a portion of the column, igniting the charge in

- contact with the separated portion and directing the separated portion into the column. 65
51. The improved method of raising water or the like, which consists in applying an explosive gaseous charge to a column of water; increasing the pressure of the explosive charge until it substantially equals the static head of the column, separating a portion of the column, introducing a resilient cushion between the separated portion and the column, igniting the charge in contact with the separated portion against the column through the intervention of the resilient cushion. 70
52. The method of utilizing energy derived from explosions, which consists in interposing an independent piston between a gaseous explosive charge and an elastic cushion, compressing the charge, igniting it, directing the explosive charge against the resilient cushion through the intervention of the piston. 75
53. The improvement in the art of utilizing heat energy, by the expansion of combustible charges against liquid, which consists in moving liquid by the action of said expansions and compressing fresh expandible charges by energy derived from previous expansions. 80
54. The improvement in the art of utilizing heat energy by the expansion of combustible charges against liquid, which consists in moving liquid by the action of said expansions and introducing and compressing fresh expansible charges by energy derived from previous expansions. 85
55. The improvement in the art of utilizing heat energy by the expansion of combustible charges against liquid, which consists in moving liquid against an elastic cushion by the action of said expansions, and compressing fresh expansible charges by energy derived from previous expansions. 90
56. The improvement in the art of utilizing heat energy by the expansion of combustible charges against liquid, which consists in moving liquid against an elastic cushion by the action of said expansions and compressing fresh expansible charges by the compressed elastic cushion. 95
57. The improvement in the art of utilizing heat energy by the expansion of combustible charges against liquid, which consists in moving liquid against an elastic cushion by the action of said expansions and compressing fresh expansible charges by the head to which the liquid has been forced by previous expansions. 100
58. The improvement in the art of utilizing heat energy by the expansion of combustible charges against liquid, which consists in moving liquid outwardly from a combustion chamber by the expansion of an ignited charge in direct contact therewith, admitting fresh liquid to the combustion chamber, causing a movement of the liquid outwardly therefrom to introduce a fresh combustible charge. 105
59. The improvement in the art of utilizing heat energy by the expansion of combustible charges against liquid, which consists in moving liquid outwardly from a combustion chamber by the expansion of an ignited charge in direct contact therewith, admitting fresh liquid to the combustion chamber and thereby expelling burnt products. 110
60. The improvement in the art of utilizing heat energy by the expansion of combustible charges against liquid, which consists in moving liquid outwardly from a combustion chamber by the expansion of an ignited charge in direct contact therewith, admitting liquid to the combustion chamber, causing a movement of the liquid outwardly therefrom to introduce a fresh combustible charge, and utilizing energy derived from previous expansions to compress fresh charges. 115
61. The improvement in the art of utilizing energy derived from the expansion of compressed expansible charges against liquid, which consists in moving liquid by the action of said expansions, and introducing and compressing successive expansible charges, in a plurality of expansion chambers alternately. 120
62. The improvement in the art of utilizing heat energy by the expansion of combustible charges against liquid, which consists in moving liquid by the action of said expansions, and introducing, compressing and igniting successive combustible charges, in a plurality of combustion chambers alternately. 125
63. The improvement in the art of utilizing heat energy by the expansion of combustible charges against liquid, which consists in moving liquid by the action of said expansions, and introducing and compressing successive combustible charges, in a plurality of coöperating combustion chambers alternately. 130
64. The improvement in the art of utilizing heat energy by the expansion of combustible charges against liquid, which consists in moving liquid by the action of said expansions, and introducing and compressing successive combustible charges, in a plurality of combustion chambers alternately, by energy derived from previous expansions. 135
65. The improvement in the art of utilizing heat energy by the expansion of combustible charges against liquid, which consists in moving liquid by the action of said expansions, and introducing and compress-

ing successive combustible charges, in a plurality of combustion chambers, alternately, said expansions acting directly upon liquid having a common path travel.

5 66. The improvement in the art of utilizing heat energy by the expansion of combustible charges against liquid, which consists in moving liquid by the action of said expansions, moving the liquid in a plurality 10 of combustion chambers so as to expel burnt products and introduce and compress combustible charges.

15 67. The improvement in the art of utilizing heat energy by the expansion of combustible charges against liquid, which consists in moving liquid by the action of said expansions, moving the liquid in a plurality 20 of combustion chambers by energy derived from previous expansions so as to expel burnt products and introduce and compress combustible charges.

25 68. The method which consists in moving a rigid piston and liquid in one direction, by the expansion of a compressed combustible charge, and actuating the liquid and the piston in the opposite direction by energy derived from previous expansions.

30 69. The method which consists in moving a rigid piston and liquid in one direction, by the expansion of a compressed combustible charge, to compress an elastic cushion, and actuating the liquid and the piston in the opposite direction by energy derived from previous expansions.

35 70. The method which consists in moving a rigid piston and liquid in one direction, by the expansion of a compressed combustible charge, to compress an elastic cushion, and actuating the liquid and the piston in the opposite direction by the expansion of the elastic cushion.

40 71. The improvement in the art of utilizing the expansive force of a compressed expansible charge in the movement of liquid, which consists in moving a body of liquid by a piston actuated by said expansive force, and utilizing the movement of said body to compress an elastic cushion.

45 72. The improvement in the art of utilizing an expansive force in the movement of liquid, which consists in moving a body of liquid by a piston actuated by said expansive force, and utilizing the energy derived from a previous expansion to introduce a fresh expansible charge.

50 73. The improvement in the art of utilizing an expansive force in the movement of liquid, which consists in moving a body of liquid by a piston actuated by said expansive force, and utilizing the energy derived from a previous expansion to introduce and ignite a fresh expansible charge.

55 74. The method which consists in expanding a compressed combustible charge against

a piston to move liquid and utilizing a return movement of the liquid to compress a fresh charge.

65 75. The method which consists in expanding a compressed combustible charge against a piston to move liquid and utilizing the inertia of the moving liquid to facilitate the expansion of the charge.

70 76. The method which consists in expanding a compressed combustible charge against a piston to move liquid and utilizing the inertia of the moving liquid to store energy.

75 77. The improvement in the art of utilizing heat expansion, which consists in moving a body of liquid by said expansion, and compressing fresh expansible charges by energy derived from previous expansions.

80 78. The improvement in the art of utilizing heat expansion, which consists in moving a body of liquid by said expansion, and introducing and compressing fresh expansible charges by energy derived from previous expansions.

85 79. The improvement in the art of utilizing heat expansion, which consists in moving a body of liquid to a greater static head by the expansion of a compressed combustible charge, and utilizing the movement of said liquid to entrain fresh liquid.

90 80. The improvement in the art of utilizing heat expansion, which consists in moving a body of liquid by the expansion of a compressed combustible charge, and utilizing the movement of said liquid to compress an elastic cushion.

95 81. The improvement in the art of utilizing the expansive force of heat which consists in moving liquid by said expansive force, in compressing expansible charges by the head of liquid moved by previous expansions and igniting the charges.

100 82. The improvement in the art of utilizing the expansive force of heat, which consists in moving liquid by said expansive force in compressing expansible charges by energy derived from previous expansions and igniting the charges.

105 83. The method which consists in compressing and igniting an expansible charge and moving liquid by the expansion of said charge to force the liquid to a greater static head.

110 84. The method of utilizing heat energy, which consists in compressing and igniting an expansible charge and moving liquid by the expansion of said charge to force the liquid against an elastic cushion.

115 85. The method which consists in compressing and igniting an expansible charge and moving liquid by the expansion of said charge and utilizing the inertia of the moving liquid to carry the liquid a distance sufficient to reduce the expansible charge to below atmospheric pressure.

86. The method which consists in compressing and igniting an expansible charge and moving liquid by the expansion of said charge and utilizing the inertia of the moving liquid to create a tendency toward vacuum to the rear thereof.

87. The method of utilizing heat energy, which consists in compressing and igniting an expansible charge and moving liquid by 10 the expansion of said charge to compress an elastic cushion.

88. The method of utilizing heat energy, which consists in compressing and igniting an expansible charge and moving liquid by 15 the expansion of said charge and utilizing energy derived therefrom for the compression of subsequent expansible charges.

89. The method of utilizing heat energy, which consists in compressing and igniting 20 an expansible charge and moving liquid by the expansion of said charge and utilizing energy derived therefrom for the introduction and compression of subsequent expansible charges.

25 90. The method of utilizing heat energy which consists in compressing and igniting an expansible charge and moving liquid by

the expansion of said charge against the liquid, and utilizing the inertia of the moving liquid in introducing fresh liquid. 30

91. The method of utilizing heat energy, which consists in compressing and igniting an expansible charge and moving liquid by the expansion of said charge and utilizing 35 energy derived therefrom for the expulsion of burnt products.

92. The method of utilizing heat energy, which consists in compressing and igniting an expansible charge and moving liquid by the expansion of said charge and utilizing 40 energy derived therefrom for the introduction of fresh liquid and the expulsion of burnt products.

93. The method of utilizing heat energy, which consists in compressing and igniting 45 an expansible charge and moving liquid by the expansion of said charge and introducing and commingling air with the moving liquid.
